LATCH BOLT AND STRIKER DEVICE

James W. Greig, Grosse Pointe Park, Mich., assignor to Hudson Motor Car Company, Detroit, Mich., a corporation of Michigan

Application April 19, 1939, Serial No. 268,777

11 Claims. (Cl. 292—340)

This invention relates to a latch bolt and striker device, particularly, although not exclusively, adapted for use in connection with the doors of automobiles and other vehicles, one object of the invention being to provide a relatively simple, durable and efficient combination door latching and striker device which in use and operation is capable of providing an easy and quiet closing door, an objective of particular desirability in connection with the steel doors of automobiles.

Another object of the invention is to combine in a single device in relatively simple and economical manner the functions heretofore accomplished in practice in a separate striker device and dovetail unit while at the same time permitting simplification of the latch bolt mechanism mounted upon the door for cooperation with the combined striker and dovetail unit of the present invention.

A further object of the invention is to provide a striker unit having a pivoted striker device adapted normally to extend into the path of the latch bolt and to be depressed or partially rotated by the bolt, when the door is closed, to permit the bolt to pass the striker member and to engage a face thereof by a wedging action whereby the striker member not only cooperates with the bolt to latch the door firmly in closed position but also assists in supporting the door rigidly against vertical and transverse movements during operation of the vehicle. The pivoted striker member not only acts as a locking step for the bolt but also functions in part as a door dovetail.

Another object of the invention is to provide a striker unit of the foregoing character having a ledge portion or projecting face, preferably inclined in contour, engageable by a preferably wedge-like member on the latch unit of the door which member cooperates with the pivoted striker to hold the door solidly in a vertical direction against chattering or vibratory movements, the wedge-like member overlying the ledge portion of the striker unit and functioning in positive manner to position the bolt and striker member as the door is closed, particularly in the event the door tends to sag or is not accurately installed within the door opening of the body.

Still a further object of the invention is to provide a latch bolt and striker assembly embodying a plurality of spaced pivoted striker members normally projecting into the path of the bolt, and cooperable with the bolt to hold

the door in successive safety and final locking positions.

A further object is to provide an assembly of the foregoing character in which the door may be closed without slamming and with a minimum of effort and quietness, while at the same time making it unnecessary to retract the bolt when closing the door.

Another object is to provide an assembly as above set forth in which the door may be readily opened by turning the handle to retract the bolt sufficiently to clear the pivoted striker member or members thereby permitting the end of the latch bolt to pass by these members as the door is pulled open.

A further object is to provide a striker and latch bolt mechanism in which the bolt and a pivoted striker member together with cooperating projecting portions of the striker and latch case plates, function conjointly in holding the door solidly and rigidly against movements of the door during operation of the vehicle.

Still another object is to provide a striker case having a transverse latch bolt passageway formed between upper and lower projecting housings within which are mounted in offset or staggered relation a pair of pivoted spring pressed striker members projecting one upwardly and the other downwardly into the passageway normally into the path of the bolt, one striker member forming a safety locking step for the bolt and the other a final locking step, the latter preferably having wedge means for take-up and for preventing chattering or vibratory noises during vehicle operation.

Other objects of this invention will appear in the following description and appended claims, reference being had to the accompanying drawings forming a part of this specification where-in like reference characters designate corresponding parts in the several views.

Fig. 1 is a fragmentary side view of a portion of an automobile body, including one of the doors thereof, embodying the present invention.

Fig. 2 is an enlarged section taken substantially through lines 2—2 of Fig. 1 looking in the direction of the arrows.

Fig. 3 is a sectional view taken substantially through lines 3—3 of Fig. 2 looking in the direction of the arrows.

Fig. 4 is a sectional view taken substantially through lines 4—4 of Fig. 3 looking in the direction of the arrows, this view illustrating the door in fully closed and latched position.

Fig. 5 is a sectional view taken substantially

through lines 5-5 of Fig. 4 looking in the direction of the arrows.

Fig. 6 is a view somewhat similar to Fig. 4 but illustrating the door in partially closed position with the latch bolt at the safety position.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawings there is illustrated, by way of example, one embodiment of the present invention as applied to an automobile body B having a swinging door D, the mechanism of the present invention comprising a latch bolt mechanism, generally designated at A, mounted upon the door, and a striker unit, generally designated at C, mounted upon the body pillar at the jamb face of the door opening.

The latch bolt mechanism which is carried by the door comprises, in the present instance, a suitable case plate 10 secured to the inner face of the inner door or lock panel 11 through the medium of screws 12. The case plate 10 includes an out-turned flange 13 which extends along the inner inclined face of the jamb 14 of the door pillar. The outer door panel is illustrated at 15 and is secured in the usual manner to the outer overlap flange of the door pillar, as shown in Fig. 2. The case plate 10 carries a retractable latch bolt 16 which has a sliding fit in an opening or slot in the flange 13 of the case plate. To the rear portion 16a of the latch bolt 16 is secured by rivets 17 a slide member 18 which has a horizontal guide slot 19 for the reception of a headed guide stud or rivet 20 secured to an angle piece 21 which in turn is fastened to an embossment in the case plate 10. The end of the slide member 18 carries a headed rivet or stud 22 extending through a horizontal slot 23 in the end of a remote control link 24, this link being connected in conventional manner to a remote control handle 24a at the inner side of the door which may be turned to retract the latch bolt. It will be understood that the remote control handle and connections to the latch bolt will be dispensed with when the inner door handle is mounted substantially opposite the outer door handle adjacent the jamb edge of the door.

The latch bolt may be retracted independently of the remote control handle through the medium of a depending extension 25 on the bolt which is engaged by a cam extension 26 of a suitable rollback journaled to turn on the case plate and controlled by a handle shaft 27 insertable into a square aperture 28 in the case plate and hub of the rollback. The shaft 27 may be turned through the medium of an outer door handle H. Mounted upon the case plate is a spiral return spring 29 for the latch bolt 16, the end 29a of the spring engaging a shoulder on the rear end of the latch bolt and adapted to return the bolt to fully extended position when the handle is released.

The combined striker and dovetail unit C comprises, in the present instance, a metallic face plate 30 and a metal backing plate 31, these parts being assembled and set in a recess 32

in the jamb edge 33 of the upright body pillar forming the frame portion at the open edge of the door opening. The face plate 30 and backing plate 31 are conjointly provided with angular slots 34 for the reception of attaching screws 35 by means of which the striker unit is attached to the pillar 33 within the recess 32. Thus, by virtue of the horizontal and vertical portions of the slots 34 the striker unit C may be readily adjusted both in a horizontal and a vertical direction so as to position the same accurately with respect to the latch bolt 16.

The face plate 30 is stamped to provide a lower transverse housing member 36 and an upper transverse housing member 37, these portions being spaced apart to provide a passageway therebetween for the bolt 16 when the door is opened and closed. The backing plate 31 is also pressed to provide shallow embossments 31a and 31b which fit into the rear open sides of the housing portions 36 and 37, this construction permitting the face plate and backing plate to be readily assembled and interlocked for ready assembly upon the body pillar. The case plate 10 is provided, in the present instance, with an upward extension 10a which is a continuation of the flange 13. This extension is pressed or drawn to provide a hollow projecting wedge member 38 overlying the upper face 37a of the upper housing member 37, the face 37a thus providing a ledge adapted to be engaged by the wedge member 38. The member 38 has a tapered or wedge shaped lower face 38a at its entering end and it will be seen from the drawings that the bottom face of the wedge member 38 rides upon the ledge face 37a of the upper housing member.

Mounted within the lower housing member 36 of the striker plate is a pivoted latch or striker member 39. This member is mounted to rotate or turn upon a pivot pin 40 riveted at its end to the embossed portion 31a of the backing plate 31, the inner end of the pin also being supported by the inner upright wall of the housing 36. The latch or striker member 39 is, in the present instance, of two arm construction having an outer arm 41 projecting freely through a slot in the upper wall or ledge face 36a of the housing member 36 and also having an inner angularly extending arm 42 adapted to engage a fixed resilient or rubber bumper or stop member 43 secured within the housing. The arm 41 is yieldingly held in extended position, as shown in Figs. 4 and 6, through the medium of a wire spring 44 coiled around the pivot pin 40, one end of the spring being hooked around the edge of the arm 41 and the other end of the spring engaging a fixed side wall of the housing 36, as shown in Fig. 4. The arm 41 of the latch 39 is provided, respectively, with outer and inner relatively inclined or tapered faces 41a and 41b. The face 41a is inclined upwardly and inwardly and lies in the path of the latch bolt 16 whereas the face 41b is reversely inclined so as to provide a safety step adapted to be engaged by the lower bevelled or tapered corner 16c of the bolt in the safety locking position shown in Fig. 6. The face 41b of the arm 41 is preferably curved with its center of curvature substantially at the pivot 40 to permit this face or edge of the arm of the striker to clear the edge of the slot in the face 36a of the housing when the arm 41 is depressed by the bolt 16.

The upper housing portion 37 of the striker plate is also provided with a latch or striker mem-

ber 45 which is mounted to turn or rotate upon a pivot pin or stud 46 having one end riveted to the embossed portion 31b of the backing plate and at its opposite end supported in an aperture in the inner upright wall of the housing 37. The upper latch member 45 is also of two arm construction having a lower arm 47 projecting downwardly through a slot in the lower wall 36a of the housing 37. The member 45 provides a second striker for the latch bolt 16, offset inwardly in staggered relation to the lower striker member 39. The arm 47 also has reversely inclined or tapered faces 47a and 47b, the face 47a lying in the path of the bolt 16 as it enters the passage between the housing members when the door is closed. The lower inclined face 47b of the arm 47 is inclined reversely to the face 41b of the arm 41 of the lower striker and is preferably curved with its center of curvature substantially at the pivot 46 to facilitate movement of the arm into the housing to clear the edge of the slot through which the arm projects. The face or edge 47b of the arm 47 of the upper striker is thus wedge-shaped for cooperation with the upper bevelled or tapered corner 16b of the latch bolt in the final locking position of the bolt as shown in Fig. 4. The upper arm 48 of the latch 45 extends within the housing 37 in position for engagement with a resilient or rubber bumper 49. The arm 47 is urged to its extended position shown in Fig. 4 by means of a wire spring 50 coiled around the pivot 46, one end of the spring being hooked over the edge of the arm 47 and the opposite end engaging the upper wall of the housing 37, as clearly shown in Fig. 4.

From the foregoing it will be understood that when the door is closed the bolt 16 will pass transversely between the projecting housing members 36 and 37 and the bolt will not retract as it moves into the preliminary and final locking positions. As the door is pushed into closed position the bolt 16 will engage successively the arm 41 of the lower projecting striker member 39 and the arm 47 of the upper projecting striker member 45. The bolt will first engage the inclined face 41a forcing the arm 41 downwardly into the housing 36 against the action of spring 44. The arm 41 will spring back into its extended position of Figs. 4 and 6 as soon as the bolt passes beyond the inclined face 41a, thus projecting the wedge-shaped locking face 41b into the path of the bolt to provide a safety locking step, as shown in Fig. 6, in the event the door is not fully closed. Further closing movement of the door will cause the bolt 16 to engage the inclined face 47a of the arm 47, thereby forcing this arm upwardly into the housing 37 against the action of the spring 50. As soon as the upper straight edge of the bolt clears the inclined face 47a the spring 50 will force the arm 47 downwardly, thereby urging the wedge face 47b against the wedge face 16b of the bolt. The path of movement of the bolt as it enters between the housing portions 36 and 37 will be governed by the upper wedge member 38 which solidly supports the door upon the upper ledge 37a of the housing member 37 and accurately positions the bolt 16 with respect to the strikers 39 and 45. In the event the door has sagged slightly the wedge member 38, assisted by the tapered face 38a and the inclination or taper of the ledge 37a, will lift the door as the wedge 38 travels inwardly upon the inclined face 37a. The cooperating inclined faces 16b and 47b of the bolt and arm of the upper striker accommodate or allow for necessary tolerances or inaccuracies

in production and it will be seen that during travel of the vehicle any tendencies of the door to vibrate or move slightly will result in the bolt tightening automatically against the wedge face 47b. Hence, the door will be supported and held solidly between the bolt 16, engaging the wedge face 47b of the arm 47, and the upper wedge 38 engaging the inclined face 37a of the housing member. It will also be seen that when the bolt is either in the position of Fig. 6 or in the position of Fig. 4 the door may be latched against any possibility of its opening since outward pressure of the bolt against either the wedge face 41b or the wedge face 47b will be opposed by reason of the fact that the striker members, when in fully extended positions, are held against rotation in an outward direction.

Rotation of the striker member 45 in a counterclockwise direction from the position of Fig. 4 is prevented by the rubber bumper 49 and also by engagement of the edge of the arm 47 with the edge of the slot in the wall 36a. In like manner rotation of the lower striker member 39 in a clockwise direction from the position of Fig. 4 is prevented by the rubber bumper 43 and also by engagement of the edge of the arm 41 with the edge of the slot in the wall 36a. The door may be opened from either of its locked positions of Figs. 4 and 6 by turning the handle to retract the bolt 16 a distance sufficient to cause its end to clear the transversely aligned striker members, whereupon the end of the bolt will move freely past the striker members. It will be understood that the bolt return spring 29 is stronger than either of the springs 44 or 50 so that in closing the door the bolt does not retract.

I claim:

1. A striker device for use in combination with a latch bolt adapted to be mounted upon a swinging door hinged at one edge to a frame structure, comprising a pivoted striker member adapted to be mounted on the frame structure and normally extending downwardly into the path of the bolt, said striker member having a substantially arcuate surface with its center of curvature substantially at the pivotal axis of the member, said arcuate surface being arranged for engagement in the locked position of the bolt with a substantially flat inclined surface on the bolt whereby upward movement of the bolt against the striker member is rigidly opposed by the striker member.

2. A striker device for use in combination with a latch bolt adapted to be mounted upon a swinging door hinged at one edge to a frame structure, comprising a pivoted striker member adapted to be mounted on the frame structure and comprising a two arm member, one arm normally extending downwardly into the path of the bolt, said last named arm of the striker member having a substantially arcuate surface with its center of curvature substantially at the pivotal axis of the member, said arcuate surface being arranged for engagement in the locked position of the bolt with a substantially flat inclined surface on the bolt whereby upward movement of the bolt against the striker member is rigidly opposed by the striker member, and a fixed resilient bumper engaged by said other arm of the striker member.

3. In a striker assembly for use in combination with a latch bolt adapted to be mounted at the free edge of a swinging door hinged at its opposite edge to a frame structure and with a wedge member on said free edge vertically spaced

with respect to the projecting end of the bolt, a striker casing adapted to be mounted on said frame structure and projecting from a surface thereof, a pivoted striker device housed within said casing and having a part extending through a slot in the casing into the path of the bolt, the upper wall of the casing forming a projecting ledge arranged for engagement by said wedge member to position the door in a vertical direction with respect to the door frame when the door is closed, said striker device and bolt having cooperating faces engageable in the locked position of the bolt to oppose vertical movement of the door in one direction, said wedge member cooperating with said ledge to hold the door against vertical movement in the opposite direction.

4. In a striker assembly for use in combination with a latch bolt adapted to be mounted at the free edge of a swinging door hinged at its opposite edge to a frame structure, a striker casing adapted to be mounted on said frame structure and projecting from a surface thereof, a pivoted striker device housed within said casing and having a part extending through a slot in the casing into the path of the bolt, a spring for normally urging said striker device into the path of the bolt, one wall of the casing forming a projecting ledge arranged for engagement by a wedge member on the free edge of the door to position the door in a vertical direction with respect to the door frame when the door is closed, said striker device and bolt having cooperating faces engageable in the locked position of the bolt to oppose vertical movement of the door in one direction.

5. In a striker assembly for use in combination with a latch bolt and with a door hinged at one edge to a door frame, a pair of pivoted spring pressed striker members adapted to be mounted in spaced relation in a direction transverse to the direction of closing of the opposite edge of the door, said members extending into the path of the bolt and adapted to be successively moved by the bolt one after the other out of the path thereof when the door is closed, each of said members adapted to be projected by its spring into the path of the bolt as the bolt moves past the member, one of said members having a wedge face cooperable with the bolt to oppose relative vertical movement thereof, and means for limiting pivotal movement of the striker members in one direction.

6. In a striker assembly for use in combination with a latch bolt adapted to be mounted at the free edge of a swinging door hinged at its opposite edge to a door frame, a pair of pivoted spring pressed striker members adapted to be mounted on the door frame and spaced transversely thereof, said members extending into the path of the bolt and adapted to be successively moved by the bolt one after the other out of the path thereof when the door is closed, each of said members adapted to be projected by its spring into the path of the bolt as the bolt moves past the member, said striker members forming successive locking steps for the bolt, and the bolt and at least one of said members having wedge faces cooperable when the bolt is in one of its locking positions.

7. A striker assembly according to claim 6 in which each striker member is a two arm member, one arm extending into the path of the bolt, the striker assembly including a fixed resilient bumper engageable by the other arm.

8. In a striker assembly for use in combination with a latch bolt adapted to be mounted at the free edge of a swinging door hinged at its opposite edge to a door frame, a pair of pivoted spring pressed striker members adapted to be mounted on the door frame and spaced transversely thereof in an offset relation, said members extending one downwardly and the other upwardly into the path of the bolt and adapted to be successively moved by the bolt one after the other out of the path thereof when the door is closed, each of said members adapted to be projected by its spring into the path of the bolt as the bolt moves past the member, said bolt and at least one of said members having wedge faces cooperable to oppose relative vertical movement thereof, and means for limiting pivotal movement of the striker members in one direction.

9. In a striker assembly for use in combination with a latch bolt and with a door hinged at one edge to a door frame, a pair of pivoted spring pressed striker members adapted to be mounted and arranged in staggered manner transversely of the door frame and in offset vertically spaced relation, said members extending into the path of the bolt and adapted to be successively moved by the bolt one after the other out of the path thereof when the door is closed, each of said members adapted to be projected by its spring into the path of the bolt as the bolt moves past the member thereby forming successive retractable locking steps for holding the door in two locking positions, said bolt being longitudinally retractable to permit the end thereof to pass freely by the striker members when the door is opened, one of the striker members forming a safety bolt locking step when the door is partially closed and the other striker member forming a final locking step when the door is fully closed.

10. In a striker assembly for use in combination with a latch bolt adapted to be mounted at the free edge of a swinging door hinged at its opposite edge to a door frame, a pair of pivoted spring pressed striker members adapted to be mounted on the door frame and arranged in staggered manner transversely of the door frame and in vertically spaced relation, said members extending into the path of the bolt and adapted to be successively moved by the bolt one after the other out of the path thereof when the door is closed, each of said members adapted to be projected by its spring into the path of the bolt as the bolt moves past the member thereby forming successive retractable locking steps for holding the door in two locking positions, each of said striker members having an arcuate face engageable by the bolt and having the center of curvature thereof at the pivotal axis of the member.

11. In a striker assembly for use in combination with a latch bolt and with a swinging door hinged at one edge to a door frame, a striker plate, a spring pressed pivoted striker member mounted on said plate, said bolt adapted to strike said member as the door is closed and to move the same out of the path of the bolt, said member being moved by its spring into said path as the bolt moves past the member, said striker member comprising a two arm member, one arm extending into the path of the bolt and the other arm into position to engage a resilient bumper.
